UNITED STATES PATENT OFFICE

159,473

WRITING BOARD OR SIMILAR ARTICLE

Roy J. Cottier, Glendale, Calif.

Application February 11, 1949, Serial No. 801

Term of patent 7 years

(Cl. D74—2)

To all whom it may concern:

Be it known that I, Roy J. Cottier, a citizen of the United States, residing in Glendale, in the county of Los Angeles, State of California, have invented a new, original, and ornamental Design for a Writing Board or Similar Article, of which the following is a specification, reference being had to the accompanying drawing, forming a part thereof.

I claim:

The ornamental design for a writing board or similar article, substantially as shown.

ROY J. COTTIER.
